(57) **CLAIM**

(22) Filed: **Aug. 9, 2002**

The ornamental design for a surface mounted electrical cable way, as shown and described.

(51) LOC (7) Cl. **13-03**

DESCRIPTION

(52) U.S. Cl. **D13/184**

FIG. 1 is a perspective view, showing my new design and illustrating the cable way of the present invention as it would appear mounted to a wall surface, the phantom line portions forming no part of the design.

(58) Field of Search .... D13/155, 156, D13/184; D8/356; 138/108, 115, 156; 16/225, 268; 52/288.1; 174/5 R, 41, 48, 66, 68.3, 72 C, 95, 97, 136, 139; 439/216

FIG. 2 is a rear quartering perspective view of the cable way illustrated in FIG. 1, the phantom line portions forming no part of the present invention.

(56) **References Cited**

FIG. 3 is a cross-sectional view of the cable way illustrated in FIGS. 1 and 2; and,

U.S. PATENT DOCUMENTS

FIG. 4 is an exploded view taken generally in the area depicted at 4 in FIG. 3.
